METAL CLIP FOR CONNECTING PLASTER BOARD PANELS AND THE LIKE

Filed June 13, 1931

FIG. 1

UNITED STATES PATENT OFFICE

ROY J. TAYLOR, OF ASHTABULA, OHIO, ASSIGNOR OF ONE-HALF TO THE AMERICAN GYPSUM CO., OF PORT CLINTON, OHIO, A CORPORATION OF OHIO

METAL CLIP FOR CONNECTING PLASTER BOARD PANELS AND THE LIKE

Application filed June 13, 1931. Serial No. 544,146.

My invention relates to improved gypsum plaster board metal supporting clips for ceiling construction preferably, although the device may be used for fastening loose ends of side walls.

One object of the invention is to provide a simple cheap device that can be put on by hand with little labor.

Another object is to provide a clip that can be stamped out by dies in large quantities at a small cost.

Other objects may readily be seen by the following description in conjunction with the drawing illustrating my device and in which:

Figure 1 is a plan view showing the clip in position. Fig. 2 is a longitudinal section on line 2—2 of Fig. 1. Fig. 3 is a perspective view showing the manner in which the device is used.

Referring to the drawing:

The plaster board panels are indicated at 1, 2, 3 and 4. The clip comprises a flat body portion 5 which is cut at intervals and bent to form a plurality of angular fins or tongues 6, 7, 8 and 9 in line on one side and 10, 11, 12 and 13 at the ends. These fins are formed by bending at right angles at 6a, 7a, 8a, 9a, 10a, 11a, 12a and 13a from the body portion 5, and the ends of the fins bent outward to form oppositely directed hooks or flanges 6b, 7b, 8b, 9b, 10b, 11b, 12b and 13b.

In use, the clip is placed between the ends of the plaster boards 1 and 3 which fit between the flanges 6b and 7b, and 8b and 9b, and the under part of the body portion 5. The plaster board panels 2 and 4 may then be slid into position against the fins 10, 11, 12 and 13 respectively and are held in this position by the flanges 10b, 11b, 12b and 13b and the projecting ends 5a and 5b of the body portion 5.

This forms a rigid structure and thus eliminates the cutting away of the loose ends and means a large saving of material.

The clip may be plastered over without obstruction.

I claim:

1. A clip for connecting plaster board panels and the like, comprising a flat plate

having a line of tongues projecting from one side thereof at the middle line of the plate, cut and bent in alternation at opposite edges of the plate with oppositely directed flanges at the ends of the tongues respectively, said flanges being parallel to the plate, to engage the edges of panels at opposite sides of the tongues.

2. A clip as in claim 1, the plate also having tongues at its ends with flanges at the respective ends directed oppositely, to engage the edges of panels at opposite ends of the plate.

In testimony whereof, I do affix my signature.

ROY J. TAYLOR.
